TREADLE CONTROL UNIT FOR DENTAL APPARATUS

Robert H. Aymar, Silver Spring, and Earl R. Weiner, Baltimore, Md., assignors to We-Mar, Inc., Hyattsville, Md., a corporation of Maryland

Filed Aug. 30, 1961, Ser. No. 66,548

Term of patent 14 years

(Cl. D24—1)

FIG. 1 is a front perspective view of a treadle control unit for dental apparatus;

FIG. 2 is a top plan view thereof;

FIG. 3 is a side elevation thereof as seen from the right of FIG. 2; and

FIG. 4 is a rear elevation thereof.

The essential features of our design reside in the portion shown in full lines.

We claim:

The ornamental design for a treadle control unit for dental apparatus, as shown and described.
